UNITED STATES PATENT OFFICE.

JOHN M. FEDDERS, OF BUFFALO, NEW YORK, ASSIGNOR TO FEDDERS MFG. CO., INC., OF BUFFALO, NEW YORK, A CORPORATION OF NEW YORK.

RADIATOR-SHUTTER.

1,329,589.

Specification of Letters Patent.

Patented Feb. 3, 1920.

Application filed February 17, 1917. Serial No. 149,231.

To all whom it may concern:

Be it known that I, JOHN M. FEDDERS, a citizen of the United States, residing at Buffalo, in the county of Erie and State of New York, have invented new and useful Improvements in Radiator-Shutters, of which the following is a specification.

This invention relates more particularly to that class of radiators which are used for cooling by air the water which is circulated around the heated parts of an explosion engine in automobiles and the like for preventing the working parts of the engine from becoming unduly heated. In the summer time the full cooling area of such radiators is usually required to obtain the maximum efficiency of the same but in the winter time it is desirable to cut down the cooling area thereof in order to compensate for the natural cooling effect of the air which is of lower temperature at this time and thereby adapt the efficiency of the radiator to the changes in temperature. It has been heretofore proposed to accomplish this purpose by covering the front side of the radiator more or less and only expose so much of the same to the air current as may be required to obtain the desired amount of cooling effect on the circulating water. Such devices, as heretofore constructed have, however, been objectionable for the reason that they were unsightly by reason of their location in front of the radiator and also by reason of the fact that the cooling effect of the air was not distributed uniformly over the radiator throughout the entire height thereof and therefore caused non-uniform expansion of the radiator.

It is the purpose of this invention to provide means for controlling the cooling effect of the air on the water passing through the radiator without detracting from the appearance of the radiator and also to accomplish this purpose in such manner that the cooling effect is distributed throughout the height of the radiator and uniform expansion of the same is secured.

In the accompanying drawings:

Figure 1 is a front elevation, partly in section, of one form of automobile radiator equipped with an air controlling device em-

bodying my invention. Fig. 2 is a horizontal section of the same, taken on line 2—2, Fig. 1. Fig. 3 is a side elevation, partly in section, of the radiator equipped with my improvements. Fig. 4 is a fragmentary vertical longitudinal section of the radiator showing the shutters which control the air supply in an open position. Fig. 5 is a fragmentary vertical transverse section, on an enlarged scale, of parts shown in Fig. 1.

Similar characters of reference indicate corresponding parts throughout the several views.

Although my improvements are applicable to radiators which may vary somewhat in details of construction that, for example, which is shown in the drawings for use in connection with my improvements comprises an upper water inlet box or header 1 which receives the heated water from the explosion engine, a lower water box or header 2 from which the cool water is returned to the engine which is to be cooled, and a plurality of radiating sections 3 which are arranged in a longitudinal row one behind another in the direction of the length of the radiator and each section comprising a plurality of upright water passages 4 which are connected at their upper and lower ends with the interior of the upper and lower water boxes and a plurality of horizontal air passages 5 extending lengthwise through the same. The water passes from the upper header downwardly through the water passages in the several radiating sections into the lower header and during such passage the same is cooled or reduced in temperature by the stream of air passing rearwardly through the air passages and in contact with the walls of the water passages. The several radiating sections of the radiator are also separated from each other by intervening air distributing spaces 6 which permit the air to spread between the adjacent radiating sections and thus insure a more uniform distribution of the cooling effect of the air on the water as it passes through the upright water conduits. In the drawings three of such radiating sections are shown in connection with the upper and lower water boxes but it is to be understood that this number

may be varied to obtain the required cooling effect which may be necessary for the engine with which the same is associated.

My improvements are designed to permit 5 of cutting off part of the cooling or radiating surface of the radiator in rear of the foremost radiating section and for this purpose the controlling means are arranged in one of the air distributing spaces arranged between 10 two adjacent radiating sections. As shown in the drawings, these controlling means are arranged in the distributing space between the foremost radiating section and the second radiating section but it is to be understood 15 that these controlling means may be otherwise arranged at some convenient point between the front and rear sides of the radiator. The particular embodiment of my improvements which are shown in the drawings 20 are constructed as follows:

7 represents a plurality of horizontal shutters, louvers or slats which are arranged in a vertical row in the first air distributing space between the first and second radiating sections. Each shutter extends practically the entire width of the radiator and is preferably constructed of sheet metal. These shutters are so mounted that they can be turned into a horizontal inoperative position in which they do not obstruct the free 30 passage of the air through the radiator from the front to the rear side of the same, as shown in Fig. 4, or the same may be turned into an upright position so that they obstruct 35 the passage of the air through that part of the radiator in rear of the shutters. In the preferred form of the shutters they are made of such width that when turned into their closed, upright or operative position each shutter laps with one edge over the edge of the adjacent shutter so as to more effectively shut off the passage of the air through the radiator sections in rear of the shutters. As shown in the drawings, this 40 is accomplished by providing the lower edge of each shutter with an off-set portion 8 which in the closed or vertical position of the shutters overhangs or overlaps the upper edge of the shutter next below the same, as 45 shown in Fig. 3.

Various means may be provided for pivotally supporting the shutters, that shown in the drawings being suitable and comprising a plurality of horizontal rock shafts or 50 spindles 9 which are arranged transversely in a vertical row between the first and second radiating section and each shaft being connected with one of the shutters between its upper and lower longitudinal edges and 55 journaled adjacent to its opposite ends in bearings 10 formed in upright supporting bars or plates 11 which are secured to opposite ends of the adjacent radiator sections. Suitable means for connecting each of these 60 shafts with its respective shutter consists in 65

stamping attaching eyes or loops 12 from the body of the shutter and securing the respective shaft in these loops by soldering or any other approved manner.

The several shutters are preferably operated in unison so that they open and close simultaneously and for this purpose the corresponding ends of the several rock shafts are provided with crank arms 13 each of which is provided at its outer end with a 70 wrist 14 which engages pivotally with an opening 15^a in an upright shifting bar or rod 15. Upon moving this shifting bar vertically in one direction the several shutters are turned into their open position while 80 upon moving this bar in the opposite direction the several shutters are simultaneously moved into an open position. By shifting the shutters so that they occupy a position between their fully opened and their fully closed position, it is possible to regulate the amount of air which is permitted to pass through the radiating sections in rear of the shutters. This adjustment of the shutters is preferably effected from some convenient 90 place, such for instance as the driver's compartment, by employing a shifting mechanism accessible to the operator. Although this shifting mechanism may be varied that for example which is shown in the drawings 95 comprises an elbow lever 16 pivoted on the lower water box and having its lower front arm pivotally connected with the lower end of the shifting bar while its upper rear arm is connected with a shifter rod 17 extending 100 rearwardly to the operator's compartment.

Owing to the arrangement of the shutters between the radiator sections the same are not visible from the front of the radiator and therefore do not detract from the appearance of the same. Furthermore it permits the cooling water to distribute itself over the entire area of the foremost radiating section and thereby causes a uniform action on the same which would not be possible if only a part of this foremost radiator section were exposed to the air. This arrangement of the shutters also permits of either fully cutting off those radiating sections in rear of the same or employing their 115 cooling efficiency to a greater or lesser extent as may be desirable.

Furthermore, if the front side of the radiator should be injured from any cause the air controlling mechanism will be unaffected 120 but remain in an operative condition so as to permit of adjusting the cooling efficiency of the radiator to suit the requirements of the engine.

This air controlling mechanism is very 125 simple in construction, the same is not liable to get out of order and it is possible to apply the same to many forms of radiators now on the market without requiring any alteration in the structure of the same.

I claim as my invention:

A radiator having a plurality of upright sections which are arranged transversely and one behind the other and adjacent sections 5 being spaced apart in a direction fore and aft of the radiator, upright plates which close opposite vertical sides of the space be-

tween two adjacent radiator sections, a plurality of coöperating shutters pivotally supported at their opposite ends on said plates 10 and adapted to swing vertically into and out of engagement with each other, and means for operating said shutters.

JOHN M. FEEDERS.
